UNITED STATES PATENT OFFICE.

HOWARD EARL HOOVER, OF CHICAGO, ILLINOIS, ASSIGNOR, BY MESNE ASSIGNMENTS, TO THE HOOVER COMPANY, OF CANTON, OHIO, A CORPORATION OF OHIO.

DISPLAY DEVICE.

Application filed August 16, 1920. Serial No. 403,707.

To all whom it may concern:

Be it known that I, HOWARD EARL HOOVER, a citizen of the United States, residing at Chicago, in the county of Cook and State of Illinois, have invented a certain new and useful Improvement in Display Devices, of which the following is a specification.

This invention relates to a display device and has for one object to provide a device for display purposes upon which an article may be mounted, so as to show at one and the same time, both the upper and the lower surfaces.

In this particular illustration, there is placed upon the device a suction sweeper, which is provided with a rotary brush. For advertising and display purposes it is desirable to show this brush in operation, and the device is so arranged that the sweeper may rest upon it in the normal upright working position, and at the same time all surfaces of the machine will be visible.

Figure 1 is a vertical section of the device.

Figure 2 is a section along the line 2—2 of Fig. 1.

Figure 3 is a side elevation of the device with a suction sweeper in position upon it, with parts shown in dotted lines.

Figure 4 is a modification showing the principle of my invention applied to a table.

Like parts are designated by like characters throughout.

A is a display box having the open side A' and transparent glass top A². B is a compartment in one end of the display box defined by partition B². B' is an electric lamp located within this compartment. C

is a mirror adjustably mounted for rotation in the box A, by means of the screws C' C'. C² is a stop mounted in the box A to limit the movement of the mirror. D is a motor driven suction sweeper having the motor driven rotary brush D'. This suction sweeper is not described in detail as it forms no part of the invention, and is shown here only as an illustration of the use of this device.

An extension A³ may be provided at the rear of the box A as shown in Fig. 1. This extension permits of a greater movement of the sweeper or other article to be displayed, and for some purposes is desirable.

The use and operation of the invention is as follows:

The display box will ordinarily be placed in some show window of a store, or in some public place. It will be so placed that passers by may look through the open side. Upon the glass top of the device will be placed a suction sweeper or some article which it is desirable to display. The image of the bottom of the sweeper will be seen through transparent glass, and will show upon the mirror immediately below it, and will be reflected out of the open side of the box and thus the under side of the sweeper is visible to passers by, at the same time that the rest of the sweeper is visible. By this means the operation of the brush in the sweeper may be clearly shown while the sweeper is standing in the ordinary upright working position. It will of course be understood, that any device might be used in connection with this display device. The mirror is so adjusted as to bring its image clearly within the view of an observer.

Although I have shown in my drawings an operative form of this device, it will be obvious that many changes, both in dimension, shape and arrangement of parts might be made without departing materially from the spirit of my invention, and I wish therefore, that my drawings be taken as in a sense diagrammatical.

The light source is so situated that it will shine directly upon the object which is located on the transparent top and thus illuminate it, but because of the partition in the box, it will not shine directly upon the mirror, nor will it be visible through the opening, it will simply illuminate the bottom of the object on display and thus a brightly lighted image will appear on the mirror and so will be seen by the public. It will be obvious that this arrangement of a mirror, a transparent supporting plate and a source of light, might be made without an enclosed casing. The various parts might be arranged in an open frame work without departing from the spirit of my invention.

In the modification or second form of the invention the transparent plate A² is mounted preferably on the forward part of a table F, and to this table is pivotally secured as at D' the mirror C, the same being held in

any desired position by any combination of apparatus as for example by the bar E pivoted at E' and provided with a slot E² and with a notched edge E³ to engage the 5 pin E⁴ on the side of the mirror.

In the arrangement of parts it is possible to move the object to be exhibited back and forth over the transparent plate and to one side of it. The table may be of any desired 10 size and so may the transparent plate. With the table the artificial lighting scheme shown in Figures 1 to 3 inclusive is omitted. The device as illustrated in Figures 1 to 3 is more particularly adapted for exhibiting 15 machines which are at rest, whereas the device shown in Figure 4 is especially adapted for exhibiting machines which are being run backwardly and forwardly in the manner in which they are run backwardly and forwardly 20 over the floor covering when in actual use. It will be understood, of course, that the device of Figures 1, 2 and 3 could be so arranged as to permit the travel of the machine over a table or an extension 25 over the top of the box to the rear of the transparent plate.

I have illustrated a transparent plate on which the object to be displayed is adapted to travel and such transparent plate is desirable 30 where the suction sweeper is to be operated over a carpet in position, for part of the demonstration or observation.

For some purposes it is desirable to remove the transparent plate and still show 35 the machine in action. When this is the case there may be substituted for the glass A² plate any transparent material which will support the object to be exhibited in upright position which will permit it to 40 travel back and forth. Thus the under part

of the object in question will be exhibited through the opening where the glass is shown in the drawings or through some part of the opening.

45

I claim:

1. A display device comprising a substantially box like structure, a transparent plate, in the top thereof, on one side of which an object to be displayed may be placed, a mirror under the transparent plate mounted in angular relation thereto, a partition in said box spaced from the top thereof, a light source positioned behind the partition and adapted to directly illuminate the bottom 50 of an object which may be placed on the transparent plate and means preventing direct illumination of the mirror.

2. In a display device, an object to be displayed, a support for the object being displayed, a reflector positioned beneath the object and in angular relation thereto, one end thereof closely approaching the object being displayed and a light source positioned below the object being displayed and rearwardly of that portion of the reflector 60 adjacent the object.

3. A display device including a transparent plate on one side of which the object to be displayed is placed and a mirror under said plate mounted so as to tilt to various 70 angles with respect to said plate, and a light source adapted to illuminate the object through the plate, but shielded from direct illumination of the mirror, and a casing 75 which encloses the mirror, and a diagonal opening in said casing.

Signed at Chicago, county of Cook, and State of Illinois, this 10th day of August, 1920.

HOWARD EARL HOOVER.
